UNITED STATES PATENT OFFICE.

THOMAS W. KIRKMAN, OF NEW YORK, N. Y.

LIGHTNING ARRESTOR AND METHOD OF MAKING THE SAME.

Application filed July 12, 1922. Serial No. 574,467.

This invention relates to lightning arresters and methods of manufacturing the same.

The principal use for such devices, as is well known, is to bring about the grounding or discharge from electrical lines of excessive potential charges, such as those caused by lightning or atmospheric electricity, in order to protect the various delicate instruments used in telegraphic, telephonic and other circuits.

It is intended by the present invention to produce a practical and compact article which, in the particular embodiment later described herein in detail, may be used in much the same manner as is the ordinary fuse, that is, in connection with an appropriate insulator block to which it may be attached by the usual spring clips to form the proper electrical connections. The invention, however, is not restricted to an arrester intended to be so used.

The main difficulty in making lightning arresters which break down on low voltage is one of construction, especially where the gap formed by the electrodes is surrounded by air. An important purpose of this invention is to furnish a method whereby lightning arresters, either of the sealed or the vacuum type, may be produced readily and efficiently with a definite or accurately measured gap of any desired length between the sparking points.

Further objects attained by the invention will be apparent from the detailed description hereinafter given and the accompanying drawing in which latter the same reference numerals indicate like parts throughout the several views, and wherein,—

Figure 1 is a horizontal section taken lengthwise of the arrester at one stage during its manufacture and before all of the parts have been finally secured in position;

Fig. 2, a fragmentary elevation of the right end of the arrester with the parts as shown in Fig. 1;

Fig. 3, a horizontal section, similar to Fig. 1, showing all of the parts secured in final position; and,

Fig. 4, a perspective of the arrester in use on an ordinary insulator block.

In the drawing there is represented at 1 a cylinder of glass or other suitable insulating material. In manufacturing lightning arresters by the method which forms a part

of the present invention, one end of cylinder 1, the right end as shown in the drawing, is closed by securing thereon a metal cup-shaped cap 2. The end of cylinder 1 is telescoped into cap 2, and the parts permanently secured together in any suitable manner but preferably by cement 3, as shown on the drawing.

It is desirable, for a purpose which will appear later, to prevent the end of cylinder 1 within cap 2 from abutting against the end of the cap. In order to properly space the parts at this point, there is provided on the peripheral flange of cap 2 an inwardly disposed projection 4. Referring to Fig. 2, it will be seen that this projection 4, which is spaced only a slight distance away from the end wall of cap 2, is formed by providing a U-shaped slit or cut in the peripheral wall or flange of the cap and then bending in the free end of the metal so formed, as shown in Fig. 1, thus forming means against which cylinder 1 abuts, when the two parts are telescoped. When the inwardly disposed projection 4 is formed, there is left in the peripheral flange of cap 2 an opening 4^a, the purpose of which will appear later. After the parts mentioned have been assembled as described, the opposite or left end of cylinder 1 is closed by a metal cup-shaped cap 5, which is somewhat similar to cap 2. This end of cylinder 1 telescopes into the peripheral flange of cap 5 and, as in the case of cap 2, the parts are then permanently secured together by cement 6, or in any other suitable manner. At this end of the arrester the end of cylinder 1 preferably, although it is not essential, abuts against the end wall of the cap 5.

In order to permit the insertion of electrode 7 which is preferably of rod form into cylinder 1, the end wall of cap 5 is provided with a central opening 8 which extends through a hollow, tapered projection 9 formed on the inner face of the end wall of cap 5, as shown in Fig. 1. Before electrode 7 is placed in position within cylinder 1, a suitable gage 10, corresponding in thickness to the desired length which it is intended to give the gap of the arrester, is inserted into the right end of cylinder 1 through opening 4^a and against the end wall of cap 2. One end of electrode 7 is then projected

into cylinder 1 through the opening 8 in cap 5 and moved forward until the end comes into contact with the left face of gage 10 against which it is firmly pressed in order to insure complete seating of the extremity of the gage against the end wall of cap 2 and thus secure the proper relative arrangement and spacing of the parts. When in this position the opposite end of electrode 7 is permanently secured in place in cap 5 in any suitable manner but preferably by means of solder 11, as shown in Fig. 3.

Electrode 7, it will thus be seen, is rigidly mounted in place within cylinder 1 and upon the withdrawal of gage 10 forms at its right extremity a definite and accurately measured sparking gap 12 with the end wall of cap 2. The left end of electrode 7 may be secured in cap 5 in any suitable manner, although it has been found in practice that the construction shown in the drawing has proven quite satisfactory.

If the arrester is to be of the sealed type, the opening 4^a in cap 2 may be closed by means of cement or solder 13. Should an arrester of the vacuum type be desired, the air within cylinder 1 may be readily exhausted by suitable means before opening 4^a is sealed as described.

Fig. 4 of the drawing is illustrative of the manner in which the arrester produced by the method above described may be used similarly to the ordinary fuse. At 14 there is shown the usual insulator block on which are mounted the spring clips 15, 16 into which the metal-capped ends of the lightning arrester snap. At 17 and 18 are the conductors, secured at their inner ends to the binding posts 19, 20 respectively, and at their outer ends (not shown) connected to the circuit intended to be protected by the arrester.

It is contemplated that numerous structural changes may be made in the arrester without departing from the scope of the invention, except as the same may be limited by the appended claims.

What is claimed is:—

50 1. A lightning arrester consisting solely of a glass tube; a metal cap closing one end of said tube and serving as an electrode; a metal cap closing the other end of said tube; and a rod electrode supported at one end by said second-mentioned cap, said electrode being disposed within said tube in spaced relation to the side walls thereof and so that its opposite end forms a gap with the end wall of said first-mentioned cap.

60 2. A lightning arrester comprising in combination, a glass cylinder open at both ends; a cylindrical metallic cap cemented on and closing one end of said cylinder, the end of said cap serving as an electrode; a second cylindrical metallic cap cemented on

and closing the other end of said cylinder, said second-mentioned cap being provided centrally of the inner face of its end wall with an integral projection, there being an opening extending through said projection 70 and the second-mentioned cap; and an electrode having one end soldered in said opening in the second-mentioned cap, said electrode being disposed within the cylinder so that its opposite end forms a gap with the 75 end wall of said first-mentioned cap.

3. A lightning arrester comprising, in combination, an insulation tube; a cup-shaped member of conductive material closing one end of said tube and serving as an electrode; a member of conductive material closing the other end of said tube; and an electrode supported at one end by said second-mentioned member, said electrode being disposed within said tube in spaced relation to 80 the side walls thereof and so that its opposite end forms a gap at one end of the tube, with the end wall of said first mentioned member.

4. A lightning arrester comprising in 90 combination, a cylinder open at both ends; a flanged cap mounted on and closing one end of the cylinder, said cap being provided with means for preventing said end of the cylinder from abutting against the end of 95 said cap when the cap is mounted thereon; closing means for the opposite end of the cylinder; and an electrode within said cylinder, one end of said electrode being supported by said closing means and the opposite end thereof forming a gap with the end of said flanged cap.

5. A lightning arrester comprising in combination, a cylinder open at both ends; a flanged cap mounted on and closing one 100 end of the cylinder, said cap being provided on the inner face of its flange with a projection for spacing said end of the cylinder from the end of said cap; closing means for the opposite end of said cylinder; and an electrode within said cylinder, one end of 105 said electrode being supported by said closing means and the opposite end thereof forming a gap with the end of said flanged cap.

6. A cap for closing the ends of lightning arresters comprising an end wall provided with a peripheral flange to receive a lightning-arrester cylinder, said flange having a portion thereof struck in so as to form a 110 projection spaced from said end wall for limiting the insertion of the lightning-arrester cylinder into said cap.

7. A lightning arrester comprising, in combination, a tube of insulating material; a cap electrode of conductive material closing one end of said tube and having its end wall spaced from the adjoining end of the tube; a cap of conductive material closing the other end of said tube; and an electrode 115

supported at one end by said second-mentioned cap, said electrode being disposed within the tube so that its opposite end forms a gap, at one end of the tube, with the end wall of said first mentioned cap.

8. That method of manufacturing lightning arresters which comprises closing one end of a cylinder with a cap; closing the opposite end of said cylinder with a cap; inserting a gage in an opening in the first-mentioned cap against the inner face of the end of said cap; inserting an electrode into an opening in the end of the second-mentioned cap with one end of the electrode against said gage within the cylinder; securing the opposite end of said electrode in place; removing said gage from said first-mentioned opening; and closing said first-mentioned opening.

20 9. That method of manufacturing lightning arresters which comprises inserting a gage within a closed cylinder against one end thereof through an opening in the side of the cylinder; inserting an electrode into said cylinder through an opening in the opposite end of said cylinder with one end of the electrode against said gage; securing the opposite end of the electrode in said second-mentioned opening; removing the gage from the cylinder; and closing said first-mentioned opening.

10. That method of manufacturing lightning arresters which comprises inserting a gage within a closed cylinder against one end thereof through an opening in the side of the cylinder; inserting an electrode into said cylinder through an opening in the opposite end of said cylinder with one end of the electrode against said gage; securing the opposite end of the electrode in said second-mentioned opening so as to seal said opening; removing the gage from the cylinder; exhausting the air from the cylinder

through said first-mentioned opening; and sealing said first-mentioned opening.

11. That method of manufacturing lightning arresters which comprises closing one end of a cylinder with a cap so that a space remains between said end of the cylinder and the end wall of said cap; closing the opposite end of said cylinder with a cap; inserting a gage in an opening in the first-mentioned cap against the inner face of the end wall of said cap; inserting an electrode into an opening in the second-mentioned cap with one end of the electrode against said gage within the cylinder; securing the opposite end of said electrode in place; removing said gage from said first-mentioned opening; and closing said first-mentioned opening.

12. That method of manufacturing lightning arresters which comprises closing one end of a container open at both ends with a cap; closing the opposite end of said container with a cap; inserting a gage in an opening in the first-mentioned cap against the inner face of the end of said cap; inserting an electrode into an opening in the second-mentioned cap with one end thereof against said gage within the container; securing the opposite end of said electrode in place; and removing said gage from the opening in said first-mentioned cap.

13. That method of manufacturing lightning arresters which comprises providing a tube with an electrode; inserting a gage within said tube against said electrode through an opening in the side of the tube; fixedly mounting a second electrode within the arrester tube with one end of the last mentioned electrode against said gage; and removing the gage from the tube.

In testimony whereof I have signed my name to this specification.

THOMAS W. KIRKMAN.
